UNITED STATES PATENT OFFICE.

JOHN F. O'CONNOR, OF CHICAGO, ILLINOIS, ASSIGNOR TO WILLIAM H. MINER, OF CHAZY, NEW YORK.

ANTIFRICTION-BEARING.

1,308,100.

Specification of Letters Patent. Patented July 1, 1919.

Application filed September 21, 1918. Serial No. 255,041.

To all whom it may concern:

Be it known that I, JOHN F. O'CONNOR, a citizen of the United States, residing at Chicago, in the county of Cook and State of Illinois, have invented a certain new and useful Improvement in Antifriction-Bearings, of which the following is a full, clear, concise, and exact description, reference being had to the accompanying drawings, 10 forming a part of this specification.

This invention relates to improvements in anti-friction bearings.

One object of the invention is to provide a simple, efficient and relatively inexpensive 15 anti-friction bearing, more particularly adapted for use as a side bearing for railway cars.

Another and more specific object of the invention is to provide a roller side bearing 20 wherein are employed a plurality of anti-friction rollers, at least one of which, after each actuation and upon removal of the pressure, will act under the influence of gravity to return all the rollers to normal 25 position in readiness for another actuation.

Another object of the invention is to provide a side bearing employing a plurality of anti-friction rollers so arranged that the pressure is always maintained approxi- 30 mately centrally of the body bolster when the side bearing proper is attached thereto.

In the drawing forming a part of this specification, Figure 1 is a vertical, sectional view, taken transversely of the body and 35 truck bolsters of a car and showing my improvements in connection therewith. Fig. 2 is a top plan view of the side bearing proper, detached. And Fig. 3 is a vertical, sectional view, taken substantially on the line 3—3 of 40 Fig. 1.

In said drawing, 10 denotes the upper portion of a truck bolster and 11 the under side of a body bolster of a railway car and between which my improved anti-friction 45 bearing is adapted to be placed.

As shown in the drawing, the bearing proper is attached to the body bolster and consists, broadly, of a retaining member A and a pair of anti-friction rollers B—B.

50 The retaining member A is preferably in the form of a casting and has an upper horizontal wall 12 with perforated ears 13 at the corners thereof by which the member is adapted to be riveted to the body bolster. 55 The member A is also provided with a pair

of downwardly extending, spaced, parallel walls 14—14 on the inner opposed sides of which are formed inwardly extending flanges or supporting tracks. Each of these guiding or supporting tracks is formed with a horizontal section, as indicated at 15, and with upwardly curved sections 16—16 at each side thereof. The member A has the upper wall thereof cut away near its ends, as indicated at 17—17, to permit the insertion of the anti-friction rollers B as herein-after explained. Furthermore, the upper wall of the member A is formed to act as a bearing plate centrally of the member A, as indicated at 18.

70 Each of the anti-friction rollers B is in the form of a cylinder with preferably integral trunnions 19—19 at the ends thereof, said trunnions 19 rolling upon the flanges 15—16. The rollers are inserted within the 75 retaining member A before the latter is applied to the bolster, as will be understood.

70 The normal position of the parts is as shown in Fig. 1, from which it will be seen that the rollers B are themselves in contact 80 but are slightly spaced from the upper bearing surface 18 of the retaining member A and the bearing surface of the truck bolster 10. When the bearing comes into action upon relative approach of the body and truck bolsters, it is evident that the rollers B will contact with the truck bolster and bearing plate 18 and the trunnions 19 will, at first, be lifted out of contact with the horizontal portions 15 of the flanges. As 85 the two bolsters move relatively to each other, as for instance, when the body bolster 11 moves to the right as viewed in Fig. 1, and the truck bolster 10 is assumed to be stationary, the anti-friction rollers will roll 90 toward the left of the retaining member A, as viewed in Fig. 1. After a slight movement, the left one of the rollers B will be relieved of pressure and will gradually be forced up the corresponding curved portions 95 16 of the flanges. With the other roller B, it will be evident that the point of contact therebetween and the body bolster will approach the center of the body bolster, a desirable feature, as will be evident to those 100 skilled in the art. Upon release of the pressure, it is evident that the end roller B which has been elevated, will automatically, under the influence of gravity, roll down the inclined flanges 16 and simultaneously force 110

the other roller back to its normal position, thus placing the bearing in condition for another actuation.

The side bearing can be made comparatively light; consists of few parts, which will not easily get out of order, and effectively returns the parts to proper position after each actuation. It will be understood by those skilled in the art that various changes and modifications may be made as, for instance, in the number of anti-friction rollers employed, without departing from the spirit of the invention.

I claim:

- 15 1. In a device of the character described, adapted to be interposed between two relatively movable elements, the combination with a retaining member adapted to be secured to one of said elements, of a plurality 20 of anti-friction rollers carried by said member, the latter being provided with roller-supporting tracks having upwardly curved end portions, said rollers having trunnions 25 coöperable with said tracks, one end roller being elevated upon the corresponding upwardly curved end portions of the tracks upon actuation of the device and thereby adapted, upon release of pressure, to itself 30 return to normal under the influence of gravity and force the remainder of the rollers also to normal position.
2. In a device of the character described, adapted to be interposed between two relatively movable elements, the combination 35 with a retaining member adapted to be secured to one of said elements, said retaining member having a pair of spaced parallel walls provided with roller-supporting

tracks, of a plurality of anti-friction rollers in peripheral contact in normal position and carried by said member and disposed between said flanges, said rollers having means coöperable with said tracks, said tracks being formed at the ends thereof with sections adapted to elevate the end rollers upon actuation of the device.

3. In a side bearing for railway cars, the combination with a retaining member adapted to be secured to a car body bolster, said retaining member having depending side walls provided with a pair of flange tracks, one on the inner face of each side wall, of a plurality of anti-friction rollers carried by said member, said anti-friction rollers having trunnions riding upon said tracks, the tracks being each formed with a horizontal central section and upwardly extending end sections, said pair of tracks being coöperable with all of said rollers.

4. In a side bearing for railway cars, in combination, a truck bolster, a body bolster opposed thereto, a retaining member secured to the body bolster, rollers associated with said retaining member, the sides of the retaining member being provided with flanges forming a track for the rollers, the said flanges being straight intermediate their ends, and upturned at their ends, the rollers being provided with end trunnions riding on the said flanges, said trunnions in the normal position of the rollers being upon the straight portions of the flanges.

In witness that I claim the foregoing I have hereunto subscribed my name this 3rd day of Sept., 1918.

JOHN F. O'CONNOR.
